SLUG CASTING MACHINE

Frank C. Frolander, Elizabeth, N. J., assignor to
Mergenthaler Linotype Company, a corporation
of New York

Application February 23, 1933, Serial No. 658,077

46 Claims. (Cl. 199—50)

This invention relates to slug casting machines, such as linotype machines of the general organization represented in U. S. Letters Patent to O. Mergenthaler, No. 436,532, wherein circulating 5 matrices and expandable spacebands are composed in line by the manipulation of a keyboard, the composed line transferred to a slotted mold for the casting of a type bar or slug, and the matrices and spacebands thereafter separated and 10 turned by a distributing mechanism to the magazines from which they started.

In these machines, when the composed line is presented to the mold, it is positioned between a pair of clamping jaws which have previously been 15 set to receive it, and while so positioned, the line is justified by the expansion of the spacebands which are driven up through the line by a so-called justification bar operated prior to the casting operation. Ordinarily, the right-hand jaw is 20 relatively fixed (having only a limited movement to operate the customary pump stop), whereas the left-hand jaw is adjustable to different positions to accord with the length of the mold slot or with the length of the composed line in its justified 25 condition. In casting under such conditions (which are the most common conditions), it is obvious that the number of matrices and spacebands composed must be sufficient to fill out the line completely (except of course for the limited 30 space allowed for justification), and hence when it is desired to cast slugs with blank spaces at the ends for indenting or centering, it is necessary to employ blanks or quads for that purpose, involving considerable annoyance and delay.

35 The general object of this invention is to adapt the machine to handle not only lines of full length as ordinarily, but in addition lines of less than full length (regardless of their actual length), so that the latter lines may be composed without 40 blanks or quads and merely with the matrices necessary for the printed matter. While various schemes of this sort have heretofore been proposed, the present invention offers many improvements upon prior arrangements in the way of 45 greater simplicity, better efficiency, and more extended scope of operation.

According to the invention, the movable supports for the two line clamping jaws (the latter being made long enough to perform their required 50 functions of closing the mold slot at the front) are actuated through two distinct trains of connections from a vertically movable rod controlled directly from the main shaft of the machine. When both jaw supports are connected to the rod, 55 they are, prior to casting, moved equidistantly

toward each other until arrested by the contact of their respective jaws with the opposite ends of the composed line (for centering) and later, after casting, restored to their original positions of maximum separation. Due provision is made 60 for disconnecting either the right-hand jaw or the left-hand jaw from the vertically movable rod, so that one or the other may be operated independently for quadding at the right or at the left as may be desired. When both jaws are disconnected, as they may be, the machine is free to function in the usual way, the right-hand jaw being left normally stationary and the left-hand jaw being adjustable by the customary devices. 65

The right-hand jaw is made rigid with its movable support, whereas the left-hand jaw is made adjustable with respect to its movable support, this adjustment permitting the two jaws to be spaced apart initially to correspond to the length of the mold slot, whether that be selected for a 70 long measure or a short measure. The same adjustment would of course be useful in other ways, as for example, in what might be termed offset centering or unequal indenting at opposite ends of the slug, that is to say centering with respect 75 to an imaginary line located to one side of the actual transverse center line of the slug.

When the clamping jaws are moved into contact with the composed line, the vertically movable actuating rod is locked in its downwardly 80 moved position by means of a toggle clamp actuated by a lost-motion device included in the operating connections for the rod, said toggle clamp acting, not directly on the rod, but, on a sleeve 85 carried by the rod. Under some conditions (as when casting from lines without spacebands) the clamping jaws are held in line-contacting positions, and under these conditions the sleeve and rod are as one and the locking of the sleeve in the downwardly moved position of the rod results 90 in the actual locking of the rod in that position. Under other conditions, however, (as when casting from lines with spacebands) in order to permit the expansion of such lines (whether used in 95 quadding or centering), the jaws are moved outwardly for a limited distance (in the present instance a variable distance of from zero to three ems) from their line contacting positions and then held in their outwardly moved positions as the line is spread out by the expansion of the 100 spacebands when driven upwardly through the line by the customary justifying devices. This is accomplished by providing for a relative movement between the vertically movable rod and its sleeve when the latter is locked in the downwardly 105 110

5 moved position of the rod, such relative movement being controlled by means of a rotary cam mounted on the sleeve, which is operated both manually and automatically in determining the extent of the relative movement and therefore the extent of the line spread or justification. In the embodiment illustrated, the manual setting of the cam is resorted to when it is desired to allow a given line spread for lines of a given length (say 10 a three em spread for a twenty-five em line), whereas the automatic operation of the cam is intended to reduce the line spread for lines of less than that given length. The actual reduction will of course depend upon the contour of the cam, 15 and in the present embodiment the cam is so designed that the reduction of the line spread will take place proportionately as the length of the line decreases from a given measure to a smaller measure (say, from three ems for a twenty-five 20 em line to one and a half ems for a twelve and a half em line). As will readily be understood, this reduction in the line spread for shorter lines is to compensate for the less number of spacebands which are included in such lines and are therefore incapable of producing the same amount of spread as would the greater number of spacebands which are included in longer or full length lines.

25 As above intimated, the right-hand jaw in casting lines of full length, is normally arranged to engage and operate a pump stop lever which permits casting to take place when the lines are properly composed, but since the right-hand jaw in the present instance is movable from its normal position for quadding or centering out of contact with the pump stop lever, provision is made for operating the latter under these conditions. In the embodiment illustrated, the left-hand jaw is provided with a yieldable section which is caused 30 to yield by the clamping of the composed line between the two jaws when the right-hand jaw is moved to the proper quadding or centering position, and this section in yielding actuates a train of connections which operate the ordinary pump 35 stop lever to permit casting. The train of connections referred to includes an interponent from which the movement of the yieldable section is imparted to the pump stop lever, and this interponent is rendered active or inactive as the right-hand jaw is or is not conditioned for quadding or centering. When the left-hand jaw is used alone 40 for quadding, the right-hand jaw is then left in its normal position and is utilized to operate the pump stop lever as the left-hand jaw in moving 45 to quadding position clamps the composed line between the two jaws. The operating connections for the pump stop lever therefore thus not only provide for the quadding and centering operations for the two line clamping jaws, but moreover they are of such character that the casting operation cannot take place during the quadding or centering unless the composed line is clamped tightly between the two jaws.

50 In casting from lines with spacebands, it has already been explained that the jaws during the justification of the line are moved back and held back from their line contacting positions, leaving a space which must be filled up by the expansion of the line. As a further feature of the invention, if the spacebands fail to fill up the space between the jaws, under the conditions stated, a safety device acts to prevent the casting operation.

55 These and other features of the invention will

be fully set forth in the detailed description to follow.

Fig. 16 is a plan view of the parts shown in Fig. 15; 120

Fig. 17 is a horizontal section taken on the line 17—17 of Fig. 14 and looking downwardly;

Fig. 18 is an elevation of the first elevator cam and the jaw operating cam, showing the relative disposition of these cams on the main shaft so as 125 to cause a slight upward lifting of the first elevator head before the jaws are separated after casting;

Fig. 19 is an enlarged view showing by the full and dotted lines the composed line before and 130 after the first elevator is raised;

The matrices X and the expandable spacebands Y (see Figs. 3 to 5) are composed in line in the assembler A under the restraining influence of a line resistant (not shown) which can be set for 135 lines of different length, all in the usual way. After the line has been composed, the assembler is raised to position the line between the fingers of the line delivery carriage B, which thereupon moves to the left (and in doing so inaugurating 140 the operation of the machine) and transfers the composed line through the intermediate channel B' into the vertically movable transporter or first elevator C slidably mounted in the vise frame D. Upon receiving the line, the first elevator immediately descends to position it between the left-hand jaw E and the right-hand jaw F and in front of the slotted mold G, which latter then advances from the rear and into contact with the line and the two clamping jaws for the slug cast- 145 150

ing operation, the line, prior to casting, being aligned and justified in the usual way when the machine is being operated under the usual conditions. After the slug has been cast, the mold 5 is carried from its horizontal casting position (as shown in Fig. 1), to a vertical ejecting position by a three-quarter rotation of the mold disc G', the first elevator in the meantime being raised to deliver the composed line to the matrix and 10 spaceband distributing devices and finally coming to rest in its original or line receiving position, as shown in Fig. 1.

As so far described, the parts and their operation, except as hereinafter noted, are or may be 15 the same as embodied in the commercial linotype machine, or as set forth in the Mergenthaler Patent No. 436,532 before referred to.

As before stated, the present invention provides devices whereby the line clamping jaws may 20 be operated automatically to cooperate with lines less than full length so as to cast slugs with blank spaces at either end, as for "quadding", or at both ends, as for "centering", and these automatic devices will now be described in detail. 25 But, first it should be stated perhaps that each of the jaws E and F is made long enough, when used alone, for quadding, to close that part of the mold slot left exposed by a short composed line, or in the absence of a composed line, 30 to close the mold slot completely. Except as thus modified, and as hereinafter noted, the two jaws are substantially the same as those employed in the commercial machines and they are mounted for movement in the vise frame D in the customary manner, being carried by supporting blocks 35 E' and F' slidable in suitable guideways formed in the vise frame D (see for example Figs. 2 and 5).

In the present embodiment, the two jaws E 40 and F are movable toward and from each other by a periodically operated part in the form of a vertically movable rod H which may be connected at its upper end to the respective jaws through the medium of two similar but oppositely disposed bell-crank levers E² and F² pivoted at E³ and F³ to the vise frame D, the longer arms of said levers being connected by short links E⁴ and F⁴ to the jaw supports E' and F', respectively, and the shorter arms of said levers being 45 arranged for connection to the rod H. According to this arrangement, when the rod H is moved downwardly from its uppermost position (which is its normal position of rest, as shown in Fig. 1), it will move the two jaws equidistantly toward 50 each other (assuming both to be connected to the rod) until they contact with the opposite ends of a composed line which has previously been positioned between them, and when the rod is moved upwardly for restoration to its position of 55 rest, it will in like manner move the jaws equidistantly away from each other to return them to their original positions of maximum separation. Since the composed lines positioned between the 60 jaws may vary in length, the actual extent of movement of the rod H will of course vary accordingly, and hence provision is made for such varied movement of the rod in its actuating connections as will presently appear.

In providing for connection and disconnection 65 of the rod H with and from the jaws E and F, the rod (see Fig. 6) is formed at its upper end with a reduced headed portion N on which is mounted, for rotation only, a grooved collar N' 70 presenting two segments N² and N³ (Figs. 12 and

13) for engagement with diametrically opposed pins N⁴ and N⁵ protruding inwardly from the extremities of the horizontal arms of the actuating levers E² and F² for the jaws E and F, respectively. When both jaws are to be connected to the rod H for centering, the collar is turned to the position shown in Fig. 13 to bring both of its segments N² and N³ into engagement with the pins N⁴ and N⁵ of the jaw actuating levers E² and F², respectively. When both jaws are to be disconnected from the rod H for regular machine operation (which is the condition shown in Fig. 1), the collar is turned to the position shown in Fig. 12 to locate the segments N² and N³ out of engagement with both of the pins N⁴ and N⁵. In connecting the rod H to either of the jaws independently, the collar is moved to intermediate positions, the segment N² being brought into engagement with the pin N⁵ of the lever F² when selecting the right-hand jaw.

While the collar N' could be turned directly by hand, a special control device is herein employed for setting the collar instantly in the required position. This device is shown in the form of a manually operable bar O mounted to slide 100 in horizontal guides O' of the vise frame D and disposed at right angles to the rod H. On its under edge the bar O is formed with a rack O² meshing with a pinion O³ fast to the forward end of a fore and aft stub shaft O⁴, journaled in the 105 vise frame D and provided at its rear end with a bevel pinion O⁵ adapted in the raised or normal position of the rod H to mesh with a right angularly disposed bevel pinion O⁶ secured to the upper side of the rotatable collar N'. The parts are 110 so proportioned that by setting the bar O in one of four different positions the collar N' will be set in as many different positions to effect the connection and disconnection of the rod H with and from the jaws in the manner above described. 115 In the present instance the setting of the bar O is effected by means of a horizontally disposed hand lever O⁷ pivoted at its rear end at O⁸ to the vise frame and loosely pivoted about midway of its length, as at O⁹, to the bar O (see Fig. 11). 120 As a guide to the operator the bar O is provided with a pointer O¹⁰ (Fig. 3) which cooperates with a scale on the vise frame bearing the designations "Reg" meaning regular machine operation, "R" meaning right jaw quadding, "C" meaning centering, and "L" meaning left jaw quadding. 125 These designations are also given in Fig. 11 to indicate the four positions of the hand lever. If desired, a detent O¹¹ (Fig. 11) may be employed to hold the bar O in its different adjusted positions, this detent being arranged to engage in one or the other of four different notches or depressions formed in the rear face of the 130 bar O.

In the operation of the machine the pinion O⁶ is moved downwardly by the rod H out of engagement with the companion pinion O⁵ (see Figs. 5 and 6) and means are provided to lock these pinions and their associated parts against operation at such times. For the pinion O⁶ there is provided a stationary arm or finger O¹² arranged to enter one of the four notches formed in the periphery of a disc O¹³ fastened to the collar N' at its lower side, this finger being arranged to stand clear of the disc in the uppermost position of the rod H but to engage the disc the instant the rod H starts its downward movement. For the pinion O⁵ there is provided (see Figs. 5 and 6) a spring pressed pawl O¹⁴ mounted in the vise frame D and arranged to 140 145 150

engage in one of the four notches formed in the periphery of a disc O^{15} attached to the pinion shaft O^4 . In the uppermost position of the rod H the pawl O^{14} is held out of engagement with the disc O^{15} by an upward extension O^{16} of the rod (see Fig. 2), but upon the lowering of the rod H the pawl is urged by its spring into engagement with the disc O^{15} . In this way the bar O or its operating handle O^7 can only be operated when the rod H is in its uppermost or normal position of rest and when the two pinions O^4 and O^6 are in mesh so that the collar N' can be turned by the operation of the bar O in connecting the rod H to either or both jaws or in disconnecting it from both. Likewise, the finger O^{12} maintains the collar N' in its set position at all times except when the two pinions are in mesh and can be operated to alter the condition of the parts.

20 The rod H is slidable in suitable bearings H^2 and H^3 of the fixed vise frame D , being provided about midway of its length with a collar H' carrying an adjusting screw which banks against the under side of the bearing H^2 when the rod is in its uppermost or normal position of rest. At its lower end the rod H is connected by a link H^9 to the forward end of a lever H^{10} having a hub portion H^{11} journaled on a pivot rod H^{12} carried by a bracket D^2 secured to the vise frame D (see Figs. 1 and 2). Fixed to and depending from the hub portion H^{11} is a barrel or cylinder H^{13} containing an expansion spring H^{14} pressing upwardly against a lug H^{15} projecting forwardly from a hub portion H^{16} of a second lever H^{17} also journaled on the pivot rod H^{12} . The lifting tendency of the spring H^{14} is resisted and overcome by the engagement of a stop lug h^{18} on the hub portion H^{16} of the second lever H^{17} with a stop lug h^{19} formed on the hub portion H^{11} of the first lever H^{10} , the effect of this arrangement being to cause the two levers to move in unison until the first lever H^{10} is arrested by a downward movement of the rod carrying sleeve H' .

45 The second lever H^{17} is connected at its rear end by a roller and groove connection H^{18} to the forward end of a bent lever H^{19} formed with separated hub portions H^{20} journaled on a pivot rod H^{21} carried by a bracket D^3 secured to the main frame of the machine, a tension spring H^{22} being connected to the lever H^{19} in advance of its pivot and serving constantly to move it downwardly at its forward end. The outer one of the hub portions H^{20} is provided with an upstanding arm H^{23} having a lateral projecting lug H^{24} which, through an adjusting screw H^{25} , bears against the rear edge of a straight lever H^{26} journaled at its lower end upon the pivot rod H^{21} and carrying at its upper end a roller H^{27} tracking upon the periphery of a rotary edge cam H^{28} fast to the main shaft H^{29} of the machine.

From the foregoing construction, it will be seen that the rotation of the cam H^{28} (which is always in a clockwise direction and which makes one complete rotation at each cycle of operation of the machine) is imparted to the rod H , through the train of connections just described, to move the rod first downwardly to effect the inward or closing movement of the jaws E and F , and then upwardly to effect the outward or separating movement of the jaws. Since, as already stated, the downward movement of the rod H will vary according to the length 75 of the composed line positioned between the

jaws, its actuating connections must be arranged to yield as the rotation of the cam H^{28} continues, and this yielding is provided for by the lost motion which takes place between the two levers H^{10} and H^{17} , the latter acting on the former through the expansion spring H^{14} which, of course, will be compressed to absorb the lost motion. The lever H^{17} , being thus permitted to partake of a full rocking movement, may be (as it is) positively connected to the cam operated lever H^{28} . The downward or jaw closing movement of the rod H takes place as the roller H^{27} runs from the low portion H^{30} of the cam onto the high portion H^{31} of the cam, while the upward or jaw separating movement of the rod H takes place as the roller runs from the high portion of the cam onto the low portion thereof, this latter movement of the parts being effected by the spring H^{22} which acts always to hold the roller H^{27} in contact with the rotary cam. It may here be noted that the high and low portions of the cam are concentric throughout approximately half the rotation of the cam, being made so in order that, in one case, the jaws will be closed before and held closed during the slug casting 100 operation and, in the other case, separated and held separated between successive slug casting operations.

In order to lock the rod H in its downwardly moved position, there is provided a toggle member J (see Figs. 5 and 7) enclosed within a box or housing D' which carries the bearing H^3 before alluded to. This toggle member J operates a clamping or grip element J' arranged to contact with a sleeve T carried by the rod H and which for purposes of the present description may be assumed to be integral with the rod. Associated with the toggle is an actuating link J^2 provided at its upper end with an adjusting screw J^3 arranged to bear upon the toggle joint. At its lower end the link J^2 is connected by a turn-buckle link J^4 to the forward laterally bent arm J^5 of the lever H^{17} before referred to. As will be noted in Fig. 5, the link J^2 is slotted as at J^6 so as to straddle the toggle joint, being encircled within the box D' by a small compression spring J^7 which normally presses upwardly through a pin or stud J^8 on the toggle joint to maintain the grip element J' in inactive position.

It will now be seen that the toggle member J is operated by reason of the lost motion which takes place between the two levers H^{10} and H^{17} , it being remembered that the former lever is the one connected to the rod H . In other words, after the lever H^{10} is arrested in its movement by the downward movement of the rod H (due of course to the contact of the jaws with the opposite ends of a composed line), the lever H^{17} continues to move to its full extent under the influence of a rotary cam H^{28} , acting in the meantime to continue its drawing down of the link J^2 . The length of the link J^2 (or what amounts to the same thing, the position of the screw J^3 thereon), is such that, during the last portion of the movement of the lever H^{17} , the screw J^3 is moved down 130 within the box D' and caused to actuate the toggle member J so as thereby to press the grip element J' under heavy pressure against the sleeve T and lock the rod H securely in its downwardly moved position. It may be explained in 140 passing that the toggle member J is so designed that its members will never pass dead center. Later, after the slug has been cast and it becomes necessary to restore the jaws to their original positions, the link J^2 is raised in advance so as to 150

unlock the rod H and its sleeve T to permit the raising of the rod, the link during the raising of the rod passing through the box or housing D' (see Fig. 2) and the spring J' acting instantly to 5 withdraw the grip element J' from engagement with the sleeve T.

Were the rod H and its sleeve T actually joined together as one (as above assumed), it is plain that there could be no spreading of the composed 10 lines after the sleeve is locked in position by the toggle member J, and in such circumstances the jaws would be locked directly in their line contacting positions, which actually happens when the lines are composed without spacebands. According 15 to this invention, however, it is proposed to move the jaws outwardly from their line contacting positions, to a limited extent, after the locking of the sleeve T in order that a composed line may be spread to a corresponding extent 20 under the expanding influence of the spacebands Y. In the present instance, provision is made for allowing the line to spread up to three ems in extent. This is accomplished, as before stated, by providing for a relative movement between 25 the rod H and the sleeve T after the latter has been locked by the toggle member J in the downwardly moved or line clamping position of the rod.

Referring particularly to Fig. 5, it will be noted 30 that at its lower end the rod H is provided with a fixed collar T' which contains an expansion spring T² encircling the rod H and pressing upwardly on the lower end of the sleeve T. This lifting tendency of the spring T², however, in the 35 downwardly moved position of the rod H, will be resisted and overcome by a rotary cam V rotatably mounted on the sleeve at its upper end and arranged in position to engage the collar H' fixed to the rod. When the cam V is set 40 with its high point in contact with the collar H', it will by reacting against the collar H', and over the opposition of the spring T², hold the sleeve T in contact with the second collar T' at the lower end of the rod. Under such a setting of 45 the cam, as will now be evident, there can be no relative movement between the rod and the sleeve, and the two parts function as if they were rigidly united, which is the condition that should exist when casting from lines without spacebands. On the other hand, when the cam is set, 50 say to bring its lowest point into contact with the collar H', then the sleeve T in the downwardly moved position of the rod H will be raised by the spring T² out of engagement with the 55 collar T', and the clearance thus provided will determine the amount of the relative movement which can take place between the rod and sleeve after the locking of the latter by the toggle member J in the manner before described. This is 60 a condition which should exist when it is desired to permit of the maximum spread of a composed line during justification, which in the case of quadded lines is three ems. When it is desired to provide for a less spread of a composed line 65 the cam V is set in an intermediate position, that is to say, in a position intermediate its lowest and highest points.

In Figs. 3, 4 and 5 the parts are shown as conditioned for quadding at the right of the line, 70 which means that the right-hand jaw F is connected alone to the rod H. Let it be assumed that the length of the composed line shown in Fig. 3 is twenty-five ems and that it is desired to allow the line to be spread or justified to the 75 full extent of three ems, which would result in

a justified line of twenty-eight ems length: When the machine is in operation the rod H will move downwardly until the jaw F is brought into contact with the composed line, as shown in Fig. 3, and since the sleeve T is carried with the rod it will move downwardly with it to the same extent. Then when the toggle member J is operated to lock the sleeve T in its downwardly moved position there will be a clearance space between the lower end of the sleeve T and the collar T' fixed to the rod, this clearance space being also shown in Fig. 3. In such condition of the parts, it is plain that the rod H is free to be moved upwardly again to an extent determined by the clearance between the lower end of the sleeve T and the rod collar T', and in carrying out the invention it is proposed to raise the rod positively to such limited extent so as thereby to move the right-hand jaw outwardly to a corresponding extent, as shown in Fig. 4. It is while the jaw is held in such outwardly moved position by the banking of the rod collar T' against the lower end of the sleeve T (which is now locked firmly in fixed position by the toggle member J) that the line is justified by the expansion of the spacebands Y produced by the upper thrust of the justification bar U in the customary way. On the basis of the foregoing assumption, the right-hand jaw will be moved outwardly to the extent of three ems and consequently the composed line will be allowed to expand to that extent. The same conditions would exist if the left-hand jaw were connected to the rod H instead of the right-hand jaw. If both jaws were connected to the rod, as for centering, the amount of spread would of course be doubled, since the same movement of the rod is imparted to each jaw independently; for that reason, when the parts are conditioned for centering, the setting of the cam V should be just half of what it would be for quadding, unless indeed it were desired to double the space in that way.

There will next be described the mechanism employed for effecting such upward limited or line-spread movement of the rod H, this mechanism being shown in Figs. 1 and 2 and in Figs. 120 14 to 17. By reference to these figures it will be seen that the lever H¹⁰, which actuates the rod H, is provided with an upwardly extending bifurcated arm H⁴⁰ having a pin H³⁹ playing in a closed slot H⁴¹ formed in the forward end of a fore and aft actuating link H⁴², the length of the slot H⁴¹ being such that the pin H³⁹ may travel from one end thereof to the other without affecting the link H⁴² as the rod H is moved back and forth by the lever H¹⁰ between its uppermost and 125 lowermost positions. As will presently appear, when the machine is in operation the link H⁴² is moved rearwardly after the sleeve T has been locked by the toggle member J in its downwardly moved position with the clamping jaws in contact with the composed line, and in its rearward movement the link will sooner or later (depending upon the extent of the downward movement of the sleeve) engage the pin H³⁹ and through the arm H⁴⁰ rock the lever H¹⁰ in a counterclockwise direction against the opposition of the spring H¹⁴. This counterclockwise rocking of the lever H¹⁰ is of course communicated to the rod H which, as a result, is moved upwardly with reference to the sleeve T until the rod collar T' banks against the lower end of the sleeve, the extent of such relative movement of the rod being, as previously stated, determined by the setting of the cam V. Compare Figs. 14 and 15. It is this 130 140 145 150

upward limited movement of the rod H which moves the line clamping jaws outwardly from their line contacting position and thus determines the final quadding or centering position 5 of the jaws when a composed line is to be spread or justified by the expansion of the contained spacebands.

Going back to the actuating connections, the link H⁴² is slidably supported in a bracket D⁴ 10 attached to the fixed machine frame and is connected by a long tension spring H⁴³ (which is more powerful than the spring H⁴⁴ above referred to) to the lower end of a lever H⁴⁴ secured to and depending from a shaft H⁴⁶ journaled in a supporting bracket D⁵ attached to the fixed machine frame at the rear. Likewise, secured to the shaft H⁴⁶, in offset relation to the lever H⁴⁴ (see Fig. 1), is a second lever H⁴⁶ having a forwardly extending arm which carries at its extremity a roller H⁴⁷ 20 arranged to cooperate with a cam H⁴⁸. While this cam might be mounted directly on the main shaft H²⁹, it is as a matter of convenience attached to the side face of the cam H²⁸ which controls the jaw closing and jaw opening movements of 25 the rod H.

As will be noted in Fig. 14, the relations of the two cams H²⁸ and H⁴⁸ is such that shortly after the former has operated the lever H²⁶ to effect the downward or jaw closing movement of the rod H and to lock the sleeve T in its downwardly moved position, the cam H⁴⁸ will be caused to engage with the roller H⁴⁷ and rock the connected levers H⁴⁶ and H⁴⁴ clockwise to draw the link H⁴² rearwardly in effecting the limited upward movement of the rod H relatively to the locked sleeve T in the manner before described. The cam H⁴⁸ maintains its engagement with the roller H⁴⁷, and hence maintains the rod H in its limited raised position, until after the composed line has 30 been justified or spread by the expansion of the spacebands. Thereafter the cam H⁴⁸ travels clear of the roller H⁴⁷, and the levers H⁴⁶ and H⁴⁴ are then restored to their original or normal position of rest by a spring H⁴⁹ connected to the lower 40 end of the lever H⁴⁴ and pulling forwardly thereon from an anchorage point in the machine frame, a stop H⁵⁰ engaged by the lever H⁴⁶ serving to locate the parts in their proper position.

In order to move the link H⁴² forwardly to its original or normal position of rest, the link is provided with a long rod H⁵¹ extending through the spring H⁴³ and connected at its rear end by a pin and slot connection H⁵² to the lever H⁴⁴. The play of the pin and slot connection is such that the actuating movement of the lever H⁴⁴ will always be transmitted to the link H⁴² through the spring H⁴³, the rod therefore acting merely as a return connection for the link from the spring H⁴⁹. While unnecessary perhaps, the rod H⁵¹ is 55 slidably supported at its forward end in a bearing formed in the bracket D⁴.

Upon the return movement of the link H⁴², the spring H⁴⁴ again comes into play and tends instantly to rock the lever H¹⁰ clockwise to move the rod H down again relatively to the locked sleeve T (it being noted that at this time the high portion H³¹ of the cam H²⁸ is still in engagement with the roller H²⁷ of the lever H²⁶), but if the line has been promptly justified or spread out by the spacebands to the full extent permitted by the outward movement of the jaws from their line contacting position, the line itself will serve to prevent such return movement of the rod by the spring H⁴⁴. On the other hand, if for any 70 reason the line has not been fully expanded by

the spacebands so as to fill out the space between the jaws, the rod H can and will be moved downwardly by the spring H⁴⁴ to whatever extent is required to close the jaws upon the composed line. In this latter event, which is an abnormal operation, the return downward movement of the rod H is utilized to prevent the casting operation from taking place, as will be subsequently described.

Coming next to the means employed for operating the line spread or justifying control cam V, reference is made particularly to Figs. 1 to 5 and 8 and 9. As clearly shown in these figures, the cam is mounted to turn on a pin or stud V' projecting laterally from a band T³ fixed to the sleeve T at its upper end. A ball member V², likewise journaled on the stud V', is pinned to the cam V and presents a forwardly extending arm V³ formed with an elongated slot V⁴. The slot V⁴ receives a pin V⁵ carried by a hand lever V⁶ pivoted at V⁷ to a vertically arranged sector plate V⁸ attached to the vise frame D. In making connection between the hand lever and the ball arm, the pin V⁵ passes through a curved guide slot V⁹ formed in the sector plate concentric to the pivot V⁷. The outer edge of the sector plate is also made concentric to the pivot V⁷ and is formed with a series of locking holes or notches to receive a spring actuated detent V¹⁰ carried by the hand lever. The locking holes are spaced 95 apart in accordance with the desired manual settings of the cam V, being designed in the present instance for one-half em settings for a range of three ems total.

When the machine is at rest, with the rod H 100 in its uppermost position, as shown in Figs. 1 and 8, the upper rod collar H' (through an adjusting screw) banks against the underside of the upper bearing member H², and a collar or band T⁴ on the lower end of the sleeve T (through an adjusting screw also if desired) banks against the underside of the lower bearing member H³, the band T⁴ being so located that in the upward movement of the rod H, it (the band) will engage the bearing member H³ far enough in advance of the engagement of the rod collar H' with the bearing member H² as to take up any clearance between the lower end of the sleeve T and the lower rod collar T'. In other words, in the uppermost position of the rod H, the sleeve T 115 will be fully depressed, so that the cam V is free to be turned by the hand lever V⁶ for the initial setting without having to overcome the resistance of the spring T², as would otherwise be necessary. When in the operation of the machine the rod H is moved downwardly, the spring T² will be allowed to exert itself in raising the sleeve T relatively to the rod, depending of course upon the initial setting of the cam V. If the cam V is set for no line spread, its high point will be 120 brought into contact with the collar H' and no raising of the sleeve can take place, but for any other setting of the cam, such upward movement of the sleeve will take place as is necessary to bring the cam into contact with the collar H' (see 130 Fig. 3).

In Figs. 1 and 8, the hand lever V⁶ is shown as having been swung downwardly to its lowermost position for a three em setting of the cam V. This being the maximum setting, the cam 135 is shown as rotated to bring its lowest portion v into contacting relation to the upper rod collar H', and under such setting of the cam the sleeve T in the downward movement of the rod H will be raised by its spring T² the maximum distance 150

- from the lower rod collar T' (see Figs. 1 and 3). Were the cam allowed to remain in this set position, the rod H, when moved upwardly by the cam H⁴⁸ after the locking of the sleeve T in its downwardly moved position, would be allowed to partake of a relative movement to the sleeve T such as to move the connected jaw or jaws back from its or their line contacting position for a distance of three ems.
- 10 In the embodiment illustrated, however, it is also proposed to rotate the cam V automatically as the rod H and sleeve T are moved downwardly to bring the clamping jaws into contact with the composed line, and it is for this reason
- 15 that the hand lever V⁶, instead of being connected directly to the cam V and therefore movable with it, is mounted upon the stationary sector plate V⁸. Being thus mounted independently of the cam V, when the cam moves downwardly with the sleeve T its slotted bail arm V³, due to its engagement with the now fixed pin V⁵, will always be rocked upwardly (see the dotted lines in Fig. 8) to turn the cam counterclockwise or in a direction to bring its higher
- 20 portions into contact with the rod collar H' and thereby reduce the space between the rod collar T' and the lower end of the sleeve.

The extent of turning of the cam will of course depend upon the extent of the downward movement of the sleeve. Thus, if the sleeve should be carried to its lowermost position, as when there is no line between the clamping jaws, the cam V will be turned to bring its highest portion v' into contact with the collar H' and in such case no clearance space will remain between the sleeve and the collar T'. On the other hand, if the sleeve should be carried only part way down, as when there is a line between the clamping jaws, the turning of the cam will vary according to the length of the line, being greater for shorter lines and lesser for longer lines.

In Figs. 3, 4 and 5, (the machine shown being a so-called thirty em machine) a twenty-five em line is shown in position between the clamping jaws and the hand lever V⁶ is shown as set for a three em line spread. Now, when the rod H is moved downwardly by the cam H²⁸, the right-hand jaw F (which alone in this instance is connected to the rod for quadding) will first be moved into contact with the composed line, as shown in Fig. 3. Since the inward movement of the jaw will be but five ems, the downward movement of the rod H will necessarily be relatively small, but small as it is, inasmuch as there is some relative movement between the bail arm V³ and the fixed pin V⁵, the cam V will turn counterclockwise to a corresponding extent, and hence to prevent the cam from effecting the position of the sleeve T, its lowermost portion v is given a concentricity sufficient to permit the cam to turn idly during this initial five em equivalent motion to the rod. As a result, when the sleeve T is locked in its downwardly moved position by the toggle member J, the rod H will be moved upwardly in relation to the sleeve to the full extent permitted by the cam V, as shown in Figs. 4 and 5, thereby moving the jaw F outwardly from its line contacting position for a distance of three ems. As before explained, the jaw will be maintained in such outwardly moved position (by the cam H⁴⁸) until the line has been spread or justified by the expansion of the spacebands Y, as indicated by the dotted lines in Fig. 4. Under such conditions, the casting

70 operation will take place in due course, and the

slug produced will be a thirty em slug bearing on its edge a line of characters justified to a length of twenty-eight ems.

The concentricity of the lowest portion v of the cam V might be greater or less than that stated, the five em allowance being mentioned only for purposes of illustration. There is a similar concentricity at the highest portion v' of the cam, as when it is set for no line spread, but the extent of this concentricity must be great enough to allow for such turning of the cam by the bail arm V³ as may take place during a full downward movement of the sleeve T in the absence of a composed line.

When the cam V is made with a five em concentricity as above described, it will be understood that the effective turning of the cam in automatically reducing the line spread does not begin until the rod H in its downward or jaw closing movement goes beyond that range, but once it does, the turning of the cam proceeds progressively as the rod descends, thereby enabling the composed line to determine for itself the amount of spread or justification which may be given to it. Thus, if as shown the rise of the cam increases gradually from its lowest portion v to its highest portion v', then the line spread is reduced proportionately as the length of the line decreases from the given measure of twenty-five ems to a less measure. For example, if the composed line is twelve and one-half ems long and the hand lever V⁶ is set for a three em spread as in Fig. 8, then the downward movement of the rod H in bringing the right-hand jaw F into contact with the composed line will result in turning the cam V counterclockwise far enough to reduce the line spread to one and one-half ems. Or again, if the line should be but five ems in length, the line spread will be cut down to three-fifths of an em. In its automatic adjustment by the rod H, the cam V will not be limited in its settings to one-half em or whole em variations, due of course to the gradual rise of the cam surface.

It may be noted that the automatic operation of the cam take place irrespective of the position in which the cam is initially set by the hand lever V⁶. For example, if the jaws E and F (by the manual adjustment of the jaw E) were originally set for a fifteen em slug as distinguished from a full length or thirty em slug, then the operator would be expected to set the hand lever V⁶ for a one and one-half line spread and in that case the intermediate point of the cam would be brought into engaging relation to the rod collar H', but since the cam at that point has no concentricity the initial downward movement of the rod H in closing the jaws upon the line will be transmitted immediately to the cam to reduce the line spread according as the length of the line drops below the given measure of fifteen ems. Obviously, such intermediate point of the cam or other intermediate points, like the lowest and highest points v and v', could be made concentric so as to provide a given tolerance for the cam in the initial downward movement of the rod H, but it is preferred to make the rise of the cam gradual owing to its automatic operation from any of its different manually set positions. Except for such universal use of the cam, its contour might be variously altered to produce different changes in line spread in its different set positions. Indeed, the cam might even be designed so as to have no concentricity at its lowest point v, and in that case the rise of

the cam might be sufficiently greater to compensate for any desired idle motion which may be given to the rod H in its initial downward movement.

5 To summarize on this branch of the invention, it will now be seen that by setting the hand lever V⁶ in any desired position the extent of the outward movement of the jaws (either one or both) may be readily determined for composed lines of a given length, and that by the automatic rotation of the cam from the rod H, such extent of the outward movement of the jaws will be automatically reduced for lines of less length, this automatic reduction being dependent upon the actual length of the composed line in use or upon the extent of the inward or line contacting movement of the jaws. It will be understood of course, that the line spread is intended only for lines containing spacebands, and 10 since the number of spacebands in a composed line will depend essentially upon the length of that line, it follows that the amount of line spread may be safely fixed with reference to the length of the line. In casting from lines without spacebands, the hand lever V⁶ will be set in its uppermost position so as to prevent relative motion between the rod H and sleeve T, the concentricity of the highest portion v' of the cam permitting the cam to be turned idly as the bail arm V³ is rocked upwardly by the downward movement of the rod H.

15 The advantage of producing a line spread is not limited to the improved typographic effect which comes from the wider spacing permitted between the words of a quadded or centered line, important as that is. By proper settings of the hand lever V⁶ and careful composition of the lines, many different effects may be obtained. Thus, by composing lines of the same length and 20 by varying the setting of the hand lever V⁶, different word spacings may be produced in different printed lines,—an effect frequently desired for centered lines. Again, by composing lines of slightly different lengths and by varying the setting of the hand lever V⁶ for different lines, all 25 of them may be spread out or justified to approximately the same length,—an effect which is often desired for quadded lines fitted about inserts. The arrangement also lends itself to the 30 casting of slugs from full length lines, as when the lines must be spread out or justified to thirty em measure, along with the casting of slugs from shorter lines, as for quadding or centering, and this without having to disconnect the rod H from the jaws. For example, if as shown in 35 Figs. 3 to 5 the right-hand jaw F is connected to the rod H for quadding, the mechanism will function without disconnecting the jaw from the rod to cast a slug with a thirty em type line. In casting such full measure slugs, the matrix 40 line will be composed as usual to a length of at least twenty-seven ems, and if therefore the hand lever V⁶ is set for a three em line spread, as it can be, the composed line will be spread 45 out or justified to the thirty em length required without quadding.

50 In the commercial machines, the slug casting operation is controlled by a pivoted lever L mounted on the machine frame and which actuates a pump stop (see Figs. 1, 3, 10 and 11). The pump stop normally stands in position to prevent casting, and the lever must be moved to the right, as viewed in the figures noted, in order to release the pump. Ordinarily, this pump releasing movement of the lever L is effected during the

55 justification of the line by a slight yielding to the right of the right-hand jaw F which engages directly with the lever, but since this jaw when used as herein for quadding or centering, must be moved away from instead of toward the lever, means are provided for operating the lever by the leftward movement of the jaw to quadding or centering position, such movement of the jaw being transmitted through the composed line to a train of connections leading to the pump stop lever.

60 The train of connections referred to includes a vertically arranged pivoted section L' carried by the left-hand jaw E and protruding inwardly beyond the matrix engaging face of the jaw. At its lower free end, the section L' is provided with a laterally projecting pin L² which bears at one edge against an inclined or cam face L³ formed on the inside of the free end of a horizontally arranged L-shaped pivoted lever L⁴, also carried by the jaw E. The free end of the lever L⁴ bears at its outer side against the rear edge of a bar L⁵ terminating at the right in the vicinity of the pump stop lever L and pivoted to the vise frame by a pair of parallel motion links L⁶. At its extreme right, the bar L⁵ carries on its upper side a roller L⁷ arranged in engagement with the lower end of a vertically disposed two-armed lever L⁸ centrally pivoted at L⁹ to the vise frame. In the upper end of the lever L⁸ there is mounted a spring actuated plunger L¹⁰ arranged in the plane of the pump stop lever L and adapted (through an interponent M later to be described) to move the lever to the right and release the pump.

65 According to the arrangement just described, when the right-hand jaw F moves to the left for quadding or centering, it pushes the composed line before it and finally clamps the line tightly against the left-hand jaw E. As the line is thus clamped between the jaws, the section L' is rocked to the left and cams the lever L⁴ forwardly, imparting a similar movement to the bar L⁵, which, because of the parallel motion links L⁶, is moved to the left. Such leftward movement of the bar L⁵ produces a clockwise 70 rotation of the lever L⁸ about its central pivot L⁹, and thereby moves the plunger L¹⁰ toward the right to actuate the pump stop lever L.

75 As above stated, the plunger L¹⁰, instead of acting directly upon the pump stop lever L, acts thereon through an interponent M. This interponent is movable forwardly and backwardly so as to stand between the plunger L¹⁰ and the lever L, as in Fig. 11, or between the jaw F and the lever L, as in Fig. 10. In the former position, which is really its active position, the interponent transmits the motion of the lever L⁸ to the pump stop lever L when the right-hand jaw F is moved to its quadding or centering position. In the latter position, which is really its inactive position (since the jaw F except for the clearance space it provides for the interponent might just as well be engaged directly with the lever L), the interponent transmits the movement of the right-hand jaw to the lever L as the jaw is caused to yield toward the right. In this connection it may be explained that such rightward yielding of the jaw F takes place when the composed line is justified between the two jaws in the regular machine operation, and also when the left-hand jaw E is moved to the right for quadding and clamps the composed line up against the right-hand jaw.

80 It is pointed out that the actuating connec- 150

tions for the pump stop lever L serve not only to operate that lever by the inward or quadding movements of the two jaws E and F but in addition, by acting through the composed line in all cases, they are rendered incapable of operating the lever unless the composed line is clamped tightly between the jaws. This safety feature of the connections is important since in quadding or centering there is always danger of a squirt due to the failure of the two clamping jaws to contact with the opposite ends of the composed line. Thus, if the matrices should become caught or wedged in the first elevator channel, the inward movement of the right-hand jaw would be blocked and that would result in the failure of the left-hand jaw to move inward far enough to contact with the line, in which event of course a squirt would almost certainly occur. Should such a contingency arise in the use of the present arrangement however, the jaw section L' would remain in its protruding condition and thus fail to actuate the pump stop lever. While the jaw section L' is inoperative when the interponent M stands between the right-hand jaw F and the pump stop lever L, the same safety feature is present, because to actuate the lever the line must be clamped tightly between the jaws, either by the expansion of the line in regular machine operation or by the inward movement of the left-hand jaw when quadding with that jaw.

The interponent M is set in one or the other of its two positions automatically by the conditioning of the parts. That is to say, when the right-hand jaw is connected to the rod H for quadding or centering, the interponent will be located between the lever L and the plunger L¹⁰ as in Fig. 11, whereas when the left-hand jaw is connected to the rod H, the interponent will be located between the lever L and the right-hand jaw F as in Fig. 10. When both jaws are disconnected from the rod H for regular machine operation, the interponent will also be located between the lever L and the right-hand jaw F as in Fig. 10.

In providing for the automatic positioning of the interponent M, it is attached to the rear end of a fore and aft slide M' mounted on the vise frame D. Through the interposition of a horizontally disposed centrally pivoted bell crank lever M² also mounted on the vise frame, the forward end of the slide M' is connected to the upper end of a vertically disposed lever M³ pivoted to the vise frame at M⁴ and having an arm M⁵ extending horizontally toward the left. The arm M⁵ carries at its extremity a pin M⁶ arranged to cooperate with a cam piece M⁷ extended to the right from the before mentioned bar O by which the jaws are connected to and disconnected from the rod H, in the manner before described. On its under edge, the cam piece M⁷ is formed with two notches or depressions M⁸ which are adapted to receive the pin M⁶ when the bar O is adjusted for left jaw quadding or regular machine operation, a spring M⁹ acting at such time to pull upwardly on the arm M⁵ and thrust the slide M' rearwardly to position the interponent M between the right-hand jaw F and the pump stop lever L. When the bar O is adjusted for right jaw quadding or centering, on the other hand, the pin M⁶ is moved out of the notches M⁸ onto the straight edge of the cam piece M⁷ and thereby caused to draw the slide M' forwardly to position the interponent M between the lever L and the plunger L¹⁰.

Here it will be convenient to describe the safety

device by which the casting operation is prevented in the event that the composed line is not expanded sufficiently to fill out the space between the clamping jaws when they are used for quadding or centering. As before explained, after the locking of the sleeve T in its downwardly moved position, as in Fig. 3, the rod H is moved upwardly by the cam H¹² for a limited distance as permitted by the setting of the cam V to back off the connected jaw (the right-hand jaw F in the instance illustrated) for a corresponding distance, as in Fig. 4. In this limited upward movement of the rod H, its lower collar T' is raised into engagement with the lower end of the locked sleeve T (compare Figs. 3 and 4) and in so doing, the collar engages a roller R' on the lower end of an arm R² pivoted to the band T⁴ secured to the sleeve T at its lower end, a pin T⁵ (see Fig. 5) passing through the sleeve and an elongated slot in the rod H to prevent rotation of the band and sleeve on the rod. The arm R² forms part of a parallel motion link R³ having a companion link R⁴ pivoted to the upper sleeve band T³, and these two links give support to a vertically disposed bar R⁵. Tracking upon the inner edge of the bar R⁵ is a roller R⁶ journaled in the extremity of the lower arm R⁷ of a long upright lever R pivotally mounted on the vise frame at R⁸. At its upper end, the lever R carries a lug R⁹ arranged to engage a bolt or set screw R¹⁰ protruding to the right from the forward end of the pump stop lever L. A spring R¹¹, connected to the lever arm R⁷ acts constantly to hold the locking lug R⁹ in engagement with the pump stop lever L and prevent the lever from being actuated, this spring R¹¹ being stronger than the customary spring which serves to maintain the pump stop lever in its normal locking position and being also stronger than the spring associated with plunger L¹⁰ included in the actuating connections for the pump stop lever.

Inasmuch as the bar R⁵ is attached to the sleeve T, it will be raised and lowered with the sleeve, the roller R⁶ running freely on the inner edge of the bar. The actual position of the sleeve T on the rod H, however, will depend upon the setting of the cam V, so that whenever the cam is set to provide for a line spread the sleeve T will be held up by its spring T² out of engagement with the lower rod collar T'—see for example Fig. 3, which shows the rod H in a downwardly moved position. In such raised position of the sleeve T relatively to the rod H, the roller R' will stand clear of the rod collar T' and hence the spring R¹¹ is free to exert itself in holding the lever R in its active position to lock the pump stop lever against actuation. Consequently, as is to be expected, when the right-hand jaw F (using the same illustration as before) is moved into contact with the composed line, as in Fig. 3, the jaw section L' will operate the lever L⁸ in the manner before described but, owing to the locking of the pump stop lever L by the lever R, the plunger L¹⁰ will be caused to yield, as indicated in Fig. 3. Later, however, when the rod H is moved upwardly to back up the jaw F as in Fig. 4, the collar T engages the roller R' and draws the bar R⁵ inwardly to overcome the action of the spring R¹¹ and move the lever R out of locking position. Thereupon, the plunger L¹⁰, under the influence of its actuating spring, is pushed outwardly and caused to actuate the pump stop lever. Then follows the justifying action which normally results in the expansion of the composed line to fill out the space between the two

80

jaws, and if this result does occur then the pump stop lever will be maintained in its actuated position by the plunger L^{10} and the casting operation may take place. If, however, the justifying action fails to expand the line sufficiently to fill out the space between the jaws, the right-hand jaw F will be moved back into contact with the composed line before the casting period arrives, and in this return movement of the jaw, the rod H will be moved downwardly with reference to the sleeve T , lowering the collar T' out of engagement with the roller R' and allowing the spring R^{11} , through the lever R , to move the lever L back to its original or pump stop position against the opposition of the plunger L^{10} , as shown in Fig. 3.

As previously noted, when the rod H is in its uppermost position or at rest, the sleeve T is held down against the collar T' by reason of the engagement of the sleeve band T^4 with the bearing member H^3 . Hence, at this time (see Fig. 1), due to the engagement of the roller R' with the collar T' , the lever R will be held in inactive position against the tension of the spring R^{11} . The rod H may therefore be disconnected from both of the vise jaws for regular machine operation, without regard to the position of the cam-setting hand lever V^6 , i. e., whether it is set for line spread or not. If the sleeve T were subject solely to the action of the cam V at the time (as it might actually be), the hand lever V^6 would always have to be adjusted to its uppermost or zero position in order to depress the sleeve far enough to render the lever R inactive. With the present arrangement, the sleeve T is automatically depressed to its lowermost position on the rod H whenever the rod is returned to its uppermost position, so that in changing the regular machine operation the attendant need only operate the hand lever O^7 by which the rod is disconnected from both jaws.

It may be explained at this point that the jaw section L' is normally returned to its protruding position, as shown in Fig. 10, after the composed line has been removed from between the jaws, by the usual actuating spring which serves constantly to hold the lever L in its active or pump stop position. On the rare occasions when the lever L is moved back to its pump stop position by the safety device R , the spring associated with the plunger L^{10} , being under tension at such times, will perform the same office. The relation of the cam surface L^3 to the pin L^2 (which latter is arranged in advance of the pivot point of the jaw section L') is such that no separate spring is required for the jaw section.

Turning to another feature of the invention, attention is directed to Figs. 2 to 5 and 10, which show the vise jaws E and F as equipped each with a depending bracket plate S formed with a horizontal lip S' slidably engaged with an overlying horizontal shelf S^2 or a long bar S^3 secured to the vise frame. The bracket plate for the left hand jaw E is attached directly thereto, since that jaw is adjustable relatively to its supporting block E' ; whereas the bracket plate for the right hand jaw F , which is non-adjustable with respect to its supporting block F' , which is attached to the block. As will be observed, the bracket plates are located adjacent the matrix contacting faces of the respective jaws and are adapted to maintain engagement with the bar S^3 (which is made long enough for that purpose) throughout the whole range of movement of the jaws. By reason of this arrange-

ment, the jaws will always be held against upward displacement during the justification of a composed line and hence maintain the proper lock-up of the line. Heretofore, when dependent solely upon the fit of their supporting blocks E' and F' in the customary guideways of the vice frame, the jaws sometimes are shifted to an inclined position by the lifting force exerted thereon by the line justifying action and leave crevices between the matrices of the line or between the end matrices and the jaws, thereby producing "squirts" or defective slugs.

There only remains to be described how the end matrices of a composed line are wiped by the clamping jaws after casting. By reference to Fig. 18, it will be seen that the first elevator C is moved vertically to and from casting position by means of a cam C' mounted on the main shaft H^2 , the cam acting in the usual way through two lever arms C^2 , C^4 . In Fig. 18, the first elevator is shown in its lowermost or casting position with the cam C' (rotating in the direction of the arrow) about to engage the lever arm C^2 and start the elevator on its upward movement. At this time, the roller H^{27} of the lever H^{26} (which operates the line clamping jaws E and F) is about to run from the high portion H^{31} of the cam H^{28} onto the low portion H^{30} so as to separate the jaws and restore them to their original positions of rest. In order, however, to permit the first elevator to partake of a slight upward movement before the roller H^{27} actually leaves the high portion H^{31} , the latter is slightly extended by the addition to the cam track of a shoe C^8 which produces the necessary time interval. In consequence, the jaws E and F will remain in their closed or line contacting position during the initial upward movement of the first elevator, and in this slight interval the composed line will be carried upward by the elevator to the dotted line position shown in Fig. 19, producing a wiping action between the end matrices of the line and the clamping jaws to remove any metal which may be adhering to the matrices or to the jaws in the casting zone. As the elevator moves on beyond the dotted line position shown in Fig. 19, the roller H^{27} descends to the lower portion H^{30} of the cam H^{28} and the two jaws are separated in readiness to receive the next line.

In the accompanying drawings the invention has been shown in preferred form and by way of example and as applied to the machine of the class stated, but obviously many modifications and alterations may be made therein and in its mode of application without departing from the spirit of the invention. It should, therefore, be understood that the invention is not limited to any specific form or embodiment, except in so far as such limitations are specified in the appended claims.

Having thus described my invention, its construction and mode of operation, what I claim is as follows:

1. In a slug casting machine, the combination of a pair of line clamping jaws, means for moving one of said jaws into contact with a composed line, means independent of the line for moving the jaw outwardly a limited distance from its line contacting position to permit the line to be expanded by spacebands to a corresponding extent, and means for holding the jaw in its outwardly moved position during the expansion of the line.

2. In a slug casting machine, the combination of a pair of line clamping jaws, one movable to-

- ward the other for quadding, means for effecting such quadding movement of the jaw, means independent of the line for moving the jaw outwardly a limited distance from its line contacting position to permit the line to be expanded by spacebands to a corresponding extent, and means for holding the jaw in its outwardly moved or quadding position during the expansion of the line.
13. 3. In a slug casting machine, the combination of a pair of line clamping jaws movable equidistantly toward each other for centering, means for effecting such centering movement of the jaws, means for moving the jaws outwardly a limited distance from their line contacting positions to permit the line to be expanded by spacebands to a corresponding extent, and means for holding the jaws in their outwardly moved or centering position during the expansion of the line.
15. 4. A combination as in claim 1, including manually adjustable means for varying the extent of the outward movement of the jaw from its line contacting position.
16. 5. A combination as in claim 1, including automatically adjustable means for varying the extent of the outward movement of the jaw from its line contacting position.
17. 6. A combination as in claim 1, including means adjustable both manually and automatically for varying the extent of the outward movement of the jaw from its line contacting position.
18. 7. In a slug casting machine, the combination of a pair of line clamping jaws, means for moving one of said jaws inwardly into contact with a composed line, said jaw being thereafter movable outwardly a limited distance from its line contacting position, means for holding the jaw in its outwardly moved position, and automatic means for varying the extent of the outward movement of the jaw in accordance with the length of the composed line.
19. 8. In a slug casting machine, the combination of a pair of line clamping jaws, means for moving one of said jaws inwardly into contact with a composed line, said jaw being thereafter movable outwardly a limited distance from its line contacting position, means for holding the jaw in its outwardly moved position, and automatically adjustable means for reducing the extent of the outward movement of the jaw as the length of the composed line decreases from a given measure to a smaller measure.
20. 9. In a slug casting machine, the combination of a pair of line clamping jaws, means for moving one of said jaws inwardly into contact with a composed line, said jaw being thereafter movable outwardly a limited distance from its line contacting position, means for holding the jaw in its outwardly moved position, manually operable means to determine the extent of the outward movement of the jaw for lines of a given length, and automatically operable means to reduce that extent of movement for lines of less length.
21. 10. In a slug casting machine, the combination of a pair of line clamping jaws, means for moving one of said jaws inwardly into contact with a composed line, said jaw being thereafter movable outwardly a limited distance from its line contacting position, means for holding the jaw in its outwardly moved position, manually operable means to determine the extent of the outward movement of the jaw for lines of a given length, and automatically operable means to reduce that extent of movement for lines of less length, said automatically operable means being controlled by the extent of the inward or line contacting movement of the jaw.
22. 11. In a slug casting machine, the combination of a pair of line clamping jaws, means for moving one of said jaws inwardly into contact with a composed line, said jaw being thereafter movable outwardly a limited distance from its line contacting position, means for holding the jaw in its outwardly moved position, and automatic means for progressively reducing the extent of the outward movement of the jaw in proportion to the extent of the inward or line contacting movement of the jaw.
23. 12. In a slug casting machine, the combination of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, and means independent of the line for effecting such limited upward movement of the rod.
24. 13. In a slug casting machine, the combination of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, and a cam movable with the rod and adjustable with reference thereto to control the extent of its upward movement after locking.
25. 14. In a slug casting machine, the combination of pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, a cam movable with the rod and adjustable with reference thereto to control the extent of its upward movement after locking, and a setting device for the cam mounted independently of the rod and cooperating therewith to adjust the cam automatically in varying the upward movement of the rod according to the extent of its downward movement before locking.
26. 15. A combination as in claim 13, wherein the vertically movable rod carries a sleeve with which the locking device engages and with reference to which the rod is movable upwardly in its limited movement after locking of the sleeve, and wherein the cam which controls the limited upward movement of the rod is mounted on the sleeve.
27. 16. In a slug casting machine, the combination of a pair of line clamping jaws, a periodically operated device connected to at least one of said jaws, said device being movable in one direction before casting to effect a closing movement of the jaws, and movable in the opposite direction

- after casting to effect a separating movement of the jaws, means for locking the periodically operated device upon completion of its jaw closing movement, said locking means permitting the 5 jaw to move outwardly a limited distance from its line contacting position, and means independent of the line for effecting such outward movement of the jaw before the expansion of the line. 17. In a slug casting machine, the combination 10 of a pair of line clamping jaws, a periodically operated device connected to at least one of said jaws, said device being movable in one direction before casting to effect a closing movement of the jaws, and movable in the opposite direction 15 after casting to effect a separating movement of the jaws, means for locking the periodically operated device upon completion of its jaw closing movement, said locking means permitting the jaw to move outwardly a limited distance from its line contacting position, means independent of the line for effecting such outward movement of the jaw before the expansion of the line, and adjustable means for controlling the extent of the outward movement of the jaw. 18. A combination as in claim 16, including as 20 an additional element a safety device to prevent the casting operation in the event that the composed line is not expanded to fill out the space between the clamping jaws during justification. 19. In a slug casting machine, the combination 25 of a pair of line clamping jaws, means for moving one of said jaws into contact with a composed line, means independent of the line for moving the jaw outwardly a limited distance from its line contacting position to permit the line to be expanded by spacebands to a corresponding extent, means for holding the jaw in its outwardly moved position during the expansion of the line, and means for preventing the casting operation 30 in the event that the line is not expanded sufficiently to fill out the space between the jaws when the aforesaid jaw is held in its outwardly moved position. 20. In a slug casting machine, the combination 35 of a pair of line clamping jaws, means for moving one of said jaws into contact with a composed line, means independent of the line for moving the jaw outwardly a limited distance from its line contacting position to permit the line to be expanded by spacebands to a corresponding extent, means for holding the jaw in its outwardly moved position during the expansion of the line, a pump 40 stop lever, means for actuating said lever to permit casting when the jaw occupies its outwardly moved position, means for actuating said lever to prevent casting by the return movement of the jaw from its outwardly moved position into contact with the line, and means for effecting such return movement of the jaw in the event that the line is not fully expanded when the jaw occupies its outwardly moved position. 21. In a slug casting machine, the combination 45 of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, the last mentioned means operating to permit a return down- 50 ward movement of the rod after the line justifying period, a pump stop lever, and means actuated by the limited upward movement of the rod for causing the pump stop lever to be operated to permit casting, said means being actuated by the return downward movement of the rod to prevent casting. 22. In a slug casting machine, the combination 55 of left hand and right hand line clamping jaws, the right hand jaw being movable toward and from the left hand jaw for quadding or centering, means for effecting such movement of the right hand jaw, means for holding said jaw in its quadding or centering position, a pump stop lever, and means independent of the holding means and actuated by the right hand jaw when in its quadding or centering position for operating the pump stop lever to permit casting. 23. In a slug casting machine, the combination 60 of left hand and right hand line clamping jaws, the right hand jaw being movable toward and from the left hand jaw for quadding or centering, means for effecting such movement of the right hand jaw, means for holding said jaw in its quadding or centering position, a pump stop lever, and means actuated by the inward movement of the right hand jaw to proper quadding or centering position for operating the pump stop lever to permit casting. 24. In a slug casting machine, the combination 65 of left hand and right hand line clamping jaws, the right hand jaw being movable toward and from the left hand jaw for quadding or centering, means for effecting such movement of the right hand jaw, a pump stop lever, and means actuated by the clamping of the composed line between the two jaws when the right hand jaw is moved to quadding or centering position for operating the pump stop lever to permit casting. 25. In a slug casting machine, the combination 70 of left hand and right hand line clamping jaws, the right hand jaw being movable toward and from the left hand jaw for quadding or centering, means for effecting such movement of the right hand jaw, a pump stop lever, a yieldable section carried by the left hand jaw and protruding inwardly beyond the matrix engaging face thereof, said section being caused to yield by the clamping of the composed line between the two jaws when the right hand jaw is moved to proper quadding or centering position, and connections actuated by the yielding section for operating the pump stop lever to permit casting. 26. In a slug casting machine, the combination 75 of left hand and right hand line clamping jaws, the right hand jaw being movable toward the left from a normal position when used for quadding or centering and capable of a slight yielding movement toward the right from said normal position when not so used, a pump stop lever, and means actuated by the movement of the right hand jaw toward the left to quadding or centering position for operating the pump stop lever, said means including an adjustable interponent through which the movement of the right hand jaw toward the left is imparted to the pump stop lever. 27. A combination as in claim 26, including as a further element means for setting the interponent in active or inactive position as required. 28. A combination as in claim 26, including as an additional element automatic means for setting the interponent in active or inactive position according as the right hand jaw is or is not conditioned for quadding or centering. 80 85 90 95 100 105 110 115 120 125 130 135 140 145 150

29. A combination as in claim 26, characterized by the fact that the interponent when set in its inactive position stands between the right hand jaw and the pump stop lever and serves in that position to transmit the yielding movement of the right hand jaw toward the right to the pump stop lever. 80
30. A combination as in claim 25, characterized by the fact that the connections actuated by 10 the yielding section of the left hand jaw are so constituted as to permit such jaw to be moved freely to different positions without disturbing the operative relation of said parts. 85
31. In a slug casting machine, the combination 15 of left hand and right hand line clamping jaws, the left hand jaw being movable variable distances toward the right from a normal position when used for quadding, and the right hand jaw under such conditions being movable toward the 20 right from its normal position, a pump stop lever operated by the yielding movement of the right hand jaw toward the right, and means for moving the left hand jaw toward the right to clamp composed lines of different lengths between the 25 two jaws and through the lines effecting the yielding of the right hand jaw to permit casting. 90
32. In a slug casting machine, the combination 30 of left hand and right hand line clamping jaws, the left hand jaw being movable independently toward and from the right hand jaw for quadding, means for effecting such movement of the left hand jaw, a pump stop lever, and means actuated by the inward movement of the left hand jaw to proper quadding position for operating the 35 pump stop lever to permit casting. 95
33. In a slug casting machine, the combination 40 of a line transporter movable downwardly to present the line in casting position and thereafter upwardly to carry the line from casting position, means for operating the transporter, a pair of line clamping jaws, one movable toward the other to close upon the composed line for quadding and then movable in the opposite direction to its normal position of rest, and means for 45 operating said clamping jaw, the two said operating means being so related that after casting a slight upward movement is imparted to the line transporter before the opening movement of the jaws takes place, whereby the end matrices of 50 the composed line are wiped by frictional contact with the faces of the jaws to remove adhering metal. 110
34. A combination as in claim 33, characterized by the fact that the transporter operating 55 means includes a rotary cam mounted on the main shaft of the machine, and that the jaw operating means likewise includes a rotary cam mounted on the main shaft, the two said cams being so disposed relatively to each other as to 60 carry out the intended operations in the sequence noted. 115
35. In a slug casting machine, the combination 65 of a pair of line clamping jaws, a vertically movable rod connected to at least one of said jaws, means for operating said rod periodically, and a toggle clamp for locking the rod in its downwardly moved position. 120
36. In a slug casting machine, the combination 70 of a pair of line clamping jaws, a vertically movable rod connected to at least one of said jaws, means for operating said rod periodically, including a pair of coaxially pivoted levers, one arranged to yield with reference to the other in the downward movement of the rod, a toggle clamp 75 for locking the rod in its downwardly moved posi- 125
- tion, and actuating connections for the toggle clamp operated by the yielding of the aforesaid lever. 130
37. In a slug casting machine, the combination of a pair of line clamping jaws, a vertically movable rod, means for operating said rod periodically, a rotatable head mounted on the upper end of said rod and by which it is connected with the jaws, means for rotating the head in selecting the jaws, said rotating means including a pinion attached to the rotatable head, a second pinion mounted in the fixed machine frame and adapted to mesh with the first pinion in the raised position of the rod, and means for operating the second pinion. 135
38. A combination as in claim 37, including as additional elements locking means for preventing the turning of the two pinions except when they are in mesh with each other. 140
39. A combination according to claim 19, wherein the casting preventing means is rendered inactive when the machine is at rest, whereby the machine may be conditioned for regular casting without interference by said means. 145
40. In a slug casting machine, the combination 100 of a pair of line clamping jaws, a periodically operated part, means for connecting said part to one of said jaws for quadding or disconnecting it therefrom for regular machine operation, a pump stop, a safety device cooperating with said pump stop to prevent casting during a quadding operation in the event that a composed line is not expanded to fill out the space between the clamping jaws during justification, and automatic means cooperating with said safety device to permit casting during a regular machine operation. 110
41. In a slug casting machine, the combination 105 of a relatively fixed supporting frame, a pair of line clamping jaws, at least one of which is mounted to slide in a guideway formed in the supporting frame, line justifying devices, and means independent of the guideway for holding the jaw against angular displacement during justification of the line. 115
42. In a slug casting machine, the combination 110 of a relatively fixed supporting frame, left hand and right hand line clamping jaws mounted in the supporting frame, the left hand jaw being 115
- slidable in a horizontal guideway formed in the frame, and means independent of its guideway for holding the left hand jaw against upward angular displacement. 120
43. In a slug casting machine, the combination 125 of a relatively fixed supporting frame, left hand and right hand line clamping jaws mounted in the supporting frame, a horizontally slidable block carrying the left hand jaw and with reference to which the jaw is adjustable, and means cooperating directly with the left hand jaw and independent of its supporting block for holding the jaw against upward angular displacement. 130
44. In a slug casting machine, the combination 130 of a relatively fixed supporting frame, left hand and right hand line clamping jaws mounted in the supporting frame, the right hand jaw being 135
- slidable in a horizontal guideway formed in the frame for quadding or centering, and means independent of the guideway for holding the right hand jaw against upward angular displacement. 140
45. A combination according to claim 42, wherein the means referred to comprise a bracket depending from the jaw adjacent its matrix contacting face and slidably engaged with a horizontal bar attached to the supporting frame. 145
46. A combination as in claim 13, wherein the 150

vertically movable rod carries a sleeve with which the locking device engages and with reference to which the rod is movable upwardly in its limited movement for locking of the sleeve, and

5 wherein the cam which controls the limited upward movement of the rod is mounted on the

sleeve, characterized by the fact that the sleeve carried by the rod is caused to occupy its lowermost position on the rod when the latter is in its uppermost position.
